UNITED STATES PATENT OFFICE.

CASIMIR DE PROSZYNSKI, OF NEW YORK, N. Y.

PROJECTING APPARATUS.

1,357,621.

Specification of Letters Patent.

Patented Nov. 2, 1920.

Application filed November 4, 1916. Serial No. 129,587.

To all whom it may concern:

Be it known that I, CASIMIR DE PROSZYNSKI, a citizen of Poland, residing at New York, in the county of New York and State 5 of New York, have invented certain new and useful Improvements in Projecting Apparatus, of which the following is a specification.

The present invention relates in general 10 to improvements in projecting apparatus, particularly to an improved form of lamp which is adapted to be associated with and used in connection with such apparatus for enlarging small pictures which are to be 15 projected on a suitable display screen.

As heretofore practised, the projection of very small pictures, such as one-quarter inch square, or even smaller, has been found to be more or less difficult, in that it required a 20 very powerful arc lamp which has such inconveniences as being inaccessible to those using the projecting apparatus, and furthermore, such arc lamps are generally found to be difficult to use. There have been at 25 attempts to solve this problem by employing an incandescent filament lamp, but such lamps are generally found to be impracticable, in that it is impossible to obtain a sufficiently strong light from the filament, and a larger 30 lighting surface cannot be used because of the small diameter of the projecting lens; moreover, the rays must go through a small picture and through the lens which is a considerable distance from the picture. If 35 an ordinary condensing lens is used between the picture and the light, such condenser should be a considerable distance from the picture and be of a small diameter, otherwise there will be quite a waste of light. Even 40 if the problem of a small, but powerful, filament could be solved, there is another side of the question which also presents serious difficulties. The filament must be placed very close to the condenser lens in order that 45 the latter may embrace a sufficient proportion of all the projected rays, in consequence of which the glass of the lamp will be subject to blackening, and after a short time, the lamp will be rendered useless. In using 50 a normal condenser calculated to obtain the best possible results, and in practice, a picture of about one-quarter inch square, the filament must be not farther than one-eighth of an inch distant from the glass of the bulb.

With such difficulties as these to overcome, 55 the present invention has for its primary object to collect nearly all rays emerging from the lighting source and throw them in one direction, so that the lighting power is many times stronger than that obtained by 60 using ordinary condensers or reflectors; and to this end, one feature of the invention consists in providing a forward reflector surrounding the opening through which the projecting beam is delivered, in such position that it will collect a considerable proportion of originally radiated rays and throw them back upon the rear reflector at an angle that will insure delivery through 65 said opening. A subordinate feature incident to the aforesaid primary object consists in arranging the filament of the lamp a considerable distance to one side of the center of the bulb, so that with proper adjustment of the bulb in the space between the reflectors, the center of illumination may be 70 located quite close to the rear reflector. 75

A further object relates to a means for safeguarding the film during the interim when the film is at rest, as at the end of 80 projection; or when, for any cause, projection is interrupted, to which end, a further feature consists in providing the rear reflector with cooling means, so that the heat rays reflected are largely subdued; or, as an 85 alternative expedient, in so mounting the rear reflector, that whenever it is not voluntarily held in full reflecting position, it will automatically swing away from such position and reduce its reflecting effect to such a 90 degree as will insure attainment of the object stated.

Further objects relate to the arrangement and coöperation of the parts which go to make up the apparatus and to certain details of construction which are employed in both the apparatus and the bulb which is used in connection therewith. 95

An illustrative embodiment of the invention is shown in the accompanying drawing, 100 and will be referred to throughout the following detail description.

In said drawing—

Figure 1 is a view partly in section of 105 the apparatus;

Fig. 2 is a rear view showing the reflector open;

Fig. 3 is a detail view of a portion of the

apparatus, illustrating the spring catch which is employed to retain the reflector in closed position;

Fig. 4 is a side elevation of the means employed for protecting the picture;

Fig. 5 is a sectional view of the lamp socket, and

Fig. 6 is a detail view of the hinge of the reflecting cover.

10 Referring to the drawings in detail, 1 represents a suitable frame which is adapted to support the casing of the apparatus which is primarily composed of two parts 2 and 3, one of which, namely the part 2, 15 comprises a hemispherical portion having an attaching flange 4 for attachment to the frame, and a comparatively narrow throat 5 tapering from the frame 1 having an enlarged deflecting space 6 which is adapted 20 to receive the bulb 7. In order that the bulb may be adjusted and then rigidly suspended within the device, the portion 2 is further constructed with a vertically presented split sleeve 8 in which is received an annular spherical cup or collar 9 in which the bulb 7 is mounted. In order to produce a 25 gripping effect between the split sleeve 8 and the annular spherical cup or collar 9, so that the bulb may be adjusted and properly suspended within the casing, the sleeve 8 has a pair of outwardly presented ears 10 which carry a suitable thumb screw 11. This thumb screw may be used to draw the 30 split portions of the sleeve together to properly clamp or grip the annular cup or collar 9. The enlarged deflecting space 6 terminates in an open side which is constructed with an annular flange 12 to which the part 3, comprising the reflector, is connected by 35 means of the hinge 13. The reflector 3 preferably comprises an arcuate shaped body, having a suitable parabolic reflecting surface 14 provided on its inner side. Surrounding this reflecting surface 14 is an annular inner 40 wall 15 which is constructed with a series of 45 ventilating openings 16. This inner wall 15 is provided with an outwardly presented annular flange 17, which is adapted to engage the annular flange 12 of the open side of the 50 enlarged deflecting space 6 and provide a light tight joint. A suitable spring catch or catches 18 may be employed for retaining the part 3 in close relation relative to the part 2. In order to produce a suitable cooling 55 surface surrounding the reflector, the part 3 is further constructed with double walls providing a water chamber 19. If necessary, part 2 may also be constructed with such a cooling arrangement. The part 60 3 has an axial opening 20 which extends transversely therethrough, the purpose of which is for ventilation. In order to fill the water chamber 19, a suitable throat 21 is provided. This throat may be closed by a 65 suitable stopper 22.

If it should be desired to avoid the use of the water jacket as a cooling arrangement, the following expedient may be resorted to, to prevent burning the film or over-heating of the lamp. The spring catch 18 (Figs. 2 and 3) may be omitted, and the hinge 13 (Figs. 2 and 6) provided with a spring 13^a, which normally tends to hold the cover 15 away from full reflecting position, so that whenever the cover is not voluntarily held in closed position, the reflector will automatically cease to deliver the heat or light energy that would endanger the film or confine the heat that will over-heat the parts. During projection, the cover will be 70 pressed lightly by the left hand of the operator and so kept closed. But as soon as projection is finished, or if it be interrupted and the hand is taken away, the cover opens automatically at least to a position where 75 it cannot reflect a sufficient amount of light through the picture to burn the film. Its position may, however, be such as will insure sufficient light for observation in focusing the picture. Instead of using the spring 13^a 80 for this purpose, the cover may be made to open by its own weight, as for instance by locating the hinge under the lamp and providing a stop that will arrest the cover in 85 partially open position; or by locating the hinge upon a bracket projecting back from the casing that would cause the cover to hang away from the casing and assume a 90 less intensively reflecting relation to the source of light whenever the cover is released.

Mounted within the tapering throat 5 of the part 2 is a round flat bottle or the like 23, the neck of which is adapted to project through a suitable opening 24 provided in 105 the top of the throat 5. This bottle is used for purposes of protecting the picture. Presented within the opening 25 of the frame 1 is a nozzle 26 which is connected to a suitable tube 27 having a bulb 28. The picture 110 which is to be enlarged is preferably presented in a position as shown at 29, that is to say, in proper position intermediate the opening 25 in the frame 1 and the lens 30. Should, for any reason, undue heat be generated within the device, a cooling effect may 115 be readily produced by means of an air blast created by the bulb 28, causing an artificial circulation to take place within the device. It is desirable that the end of the nozzle 26 120 assume a position close to the picture in order that the air blast which is produced by the bulb 28 will cool the picture and be deflected thereby through the interior of the device. As heretofore stated, circulation is 125 induced by means of the openings 16 provided in the annular inner wall 15. It is to be noted that the particular shape and construction of the part 3, especially the outer wall thereof, will provide a secondary 130

precaution to prevent the light from filtering from the interior of the device. Again referring to the particular construction of the bulb, it is to be noted that by means of 5 the particular spherical shape of the annular collar 9, the bulb may be readily adjusted within the sleeve 8 without permanently clamping the ears 10. To observe this adjustment, and to be sure that the filament of the bulb is exactly in the center of 10 the reflector, the annular flange 12 is provided with four slits or cuts 31, whereby the filament may be properly adjusted by looking across two of these opposite slits. 15 It is to be noted that the filament of the bulb is positioned at one side of the axis of the bulb which brings it very near that wall of the bulb which is presented immediately in front of the parabolic reflector 14 so as 20 to bring the center of illumination at the center of the parabolic reflector, whereby the rays may be directed toward the lens.

When the proper adjustment of the filament is obtained, it may be made permanent 25 by producing a clamping effect between the split sleeve 8 and the annular spherical collar 9. The electric connection to the bulb may be made in any suitable manner. Above the spherical neck 9, the shank of the lamp has 30 the terminal pins 9^a that are received in the sockets 9^b of a cap 9^c.

When the bulb is properly adjusted within the device, the filament thereof is placed exactly in the center of the hemispherical part 35 2 of the casing, and in the same plane with the axis of the reflecting surface (preferably parabolic) of the part 3. All the rays directed rearwardly from the filament are caught by the reflector and reflected in a 40 manner to converge at one point in proximity to the lens. Those rays, directed by the filament toward the inner wall of the enlarged deflecting space 6, are returned backward past the filament until they meet the 45 parabolic reflector which throws them forward and focuses them on the lens as in the case of the rays first mentioned. By means of this particular adjustment of the bulb and the filament, and together with the particular arrangement of the reflecting walls, 50 nearly all the rays emerging from the filament ultimately reach one point. In order to avoid prismatic action or the dispersion of the rays by the glass forming the bulb, 55 the bulb is preferably constructed of a large diameter and made to substantially fill the space within the casing. As heretofore stated, this apparatus is designed and constructed particularly for the projection of 60 small pictures, but it may be adapted to any other use where it is necessary or desirable to concentrate a strong light on a small space.

As heretofore stated, the embodiment of 65 the invention described in detail, is merely

shown for the purpose of illustration. Certain changes can be made without departing from the spirit of the invention. For instance, instead of the air blast produced by the bulb 28 and its associated parts, a suitable fan may be used to play against the interior of the device at all times. Other such changes may also be made; hence, the novelty involved should be construed and interpreted by the scope of the subjoined 75 claims.

I claim:

1. A projecting apparatus comprising a pair of reflectors, one of which is of less diameter than the other, a projecting lens 80 in line with an opening in one of the reflectors, and an incandescent lamp having its center of illumination positioned at one side of the bulb adjacent to the reflector distant from the lens.

2. A projecting apparatus comprising a casing formed by two reflectors one of them substantially spherical and the other of said reflectors having a concavity of smaller diameter than the first reflector with an annular flange projecting therefrom and provided with reflecting surface, a projecting lens concentric with said reflectors, and an incandescent lamp interposed between the two reflectors with its illuminating filament 95 disposed to one side of the bulb adjacent to one of the reflectors.

3. In combination a projecting lens, a casing formed by two oppositely disposed reflectors, one of which is spherical and the other of non-spherical form and of less circumference than the first, an incandescent lamp between the two reflectors having its center of illumination disposed to one side of the bulb and in close proximity to one of the reflectors, the bulb of the lamp having a diameter substantially as large as the smaller reflector, and one of said reflectors having indicators upon its edges for centering the light.

4. In a projecting apparatus, the combination with a front casing having a projecting orifice, of a light emitting member within said casing, and a back cover for said casing having a concave portion opposite said light emitting member and a flat portion disposed in a diametrical plane which is no farther from the orifice than is said light emitting member, said flat portion having ventilating holes.

5. In a projecting apparatus, the combination with a front casing, of a light emitting member within said casing, and a back cover for said casing having a concave portion opposite said light emitting member and a flat portion disposed in the diametrical plane which passes through said light emitting member, said flat portion having ventilating holes.

6. In a projecting apparatus, the combina-

- tion with a front casing, of a light emitting member within said casing, and a back cover for said casing having a concave portion opposite said light emitting member and a flat portion disposed in the diametrical plane which passes through said light emitting member, said flat portion having ventilating holes, and a supplementary cover to stop the light which is projected through said holes.
- 10 7. In a projecting apparatus, the combination of a front casing, comprising a reflector, a light emitting member, a back cover for said casing having a concave reflecting portion opposite said light emitting member to catch substantially all of the reflected rays from said first mentioned reflector, and a flat annular flange around said concave portion being disposed outside of the reflecting area of said first mentioned reflector and in the diametrical plane which passes through said light emitting member, and ventilating holes in said flange.
8. In a projecting apparatus, the combination of a front casing, comprising a reflector, a light emitting member, a back cover for said casing having a concave reflecting portion opposite said light emitting member to catch substantially all of the reflected rays from said first mentioned reflector, and a flat annular flange around said concave portion being disposed outside of the reflecting area of said first mentioned reflector and in the diametrical plane which passes through said light emitting member.
- 35 9. In a projecting apparatus, the combination with a casing and a light-emitting member, of a support for said light-emitting member, having a spherical neck, and a clamping device carried by said casing and comprising members disposed around said neck in parallel relation to the longitudinal axis of said clamping device, and means for compressing said members upon said spherical neck.
10. In a projecting apparatus, the combination with a casing and a light emitting member, of a support for said light emitting member having a spherical neck, a flexible cylindrical collar mounted on said casing, and means for compressing said collar on 50 said spherical neck.
11. In a projecting apparatus, the combination with a casing and an electric lamp having a spherical neck, a flexible cylindrical collar mounted on said casing and means 55 for compressing said collar on said spherical neck.
12. In combination, a reflector, a light element coating therewith, a socket member carrying said light element and having a ball portion, and a clamping ring, the ball portion of said socket member being seated in said ring and being adjustable with said light element about a point or longitudinally with respect to said clamping ring. 60
13. In combination, a reflector, a light element coating therewith, a socket member carrying said light element and having a ball portion, a clamping ring, the ball portion of said socket member being seated in 70 said ring and being adjustable with said light element about a point or longitudinally with respect to said clamping ring, and means coating with said clamping ring to secure said socket member in adjusted position. 75

The foregoing specification signed at New York city, N. Y., this 10th day of July, 1916.

CASIMIR DE PROSZYNSKI.
